UNITED STATES PATENT OFFICE.

HARRY A. PRINDLE, OF EAST ORANGE, NEW JERSEY.

CENTRIFUGAL PUMP.

Application filed January 4, 1923. Serial No. 610,634.

To all whom it may concern:

Be it known that I, HARRY A. PRINDLE, a citizen of the United States, and a resident of East Orange, county of Essex, and State of New Jersey, have invented certain new and useful Improvements in Centrifugal Pumps, of which the following is a specification.

Centrifugal pumps of the kind known as sump or bilge pumps are generally placed horizontally in the sump pit and are hung by suitable supports from a sump cover plate. Such pumps, owing to their inaccessible position and also to the fact that they are often required to handle liquids carrying more or less suspended solid materials, as sand or sewage, must be not only rugged and simple in construction, but reliable in operation. To these qualities must be added if possible cheapness of construction and efficiency of performance. And to more nearly attain these results is the object of the present invention. Sump pumps well known in the art have been made of the ordinary volute type with the tangential discharge on one side leading up through a discharge pipe to and through a plate cover. Such pumps have to be well braced to overcome the reactive thrust due to the side discharge and even when so braced they are subjected to stresses tending to bend the shaft and this gives rise to vibrations that are detrimental to the efficiency and the durability of the pump.

It can readily be seen that any bracing that would hold the shaft straight for any given output, would, due to the elasticity of the bracing, be either too slack, or too tight, for other outputs, so that every impulse or change of load, will be the cause of vibrations, that may be quite objectionable. Besides a separate delivery pipe, off to one side, renders the pump awkward to handle in restricted pits.

These objections have given rise to a class of sump pumps in which the suspending member is made use of as a discharge pipe; the shaft being journaled in a hub in the lower end of this pipe; the hub being in turn supported by vanes from the pump casing. Such pumps may either have an impeller of the enclosed type, or of the semi-enclosed type; but in either case they are made to deliver the water all around the periphery of the impeller chamber, from whence the water passes up between the hub

supports, into the central pipe, that forms at once the discharge pipe, the pump support and the shaft guide. In this case the water, as it is discharged from the impeller, strikes violently against the hub vanes and is compelled to abruptly change its direction of flow and also to suddenly change its velocity. This results in eddy and friction losses that seriously impair the efficiency of the pump and cause more or less vibration. Could the volute form of discharge with its gradual change of direction and volume be introduced such losses would not be so marked.

In a pump constructed according to my present invention I retain the advantages of the volute form of delivery from the impeller to the discharge and by using a balanced number of such volutes, so constructed as to first lead off circumferentially, in the direction of the line of flow, then to turn inwardly and join the central discharge, I attain at once a balanced effort that imparts no bending stress to the pump support and yet gives the desired efficiency.

In the accompanying drawings which illustrate an embodiment of my invention in the form of a sump pump,

Fig. 1 is a side elevation of the pump;

Fig. 2 is a vertical axial section showing the discharge pipe and certain details of the driving members;

Fig. 3 is a vertical axial section of the pump;

Fig. 4 is a plan and partial section of the pump casing;

Fig. 5 is a side view and partial section of the pump casing showing the volute discharge passage;

Fig. 6 is a horizontal section of the pump casing on the plane of the line 6-6 shown in Fig. 3;

Fig. 7 is a vertical radial section on the line 7-7 of Fig. 4; and

Fig. 8 a similar section on the lines 8-8, Fig. 4.

Referring to Fig. 1 a sump pit is shown at 1 and a pit cover at 2. At 3 is shown as indicated a usual form of control float for starting and stopping the pump. The pump 4 is supported by a pipe 5 from the cover-plate 2. Mounted on the cover-plate is a base plate 6 which serves as a support for an electric motor 7. This base plate has cast integral with it, the discharge elbow 8 to which a discharge pipe 9 may be

secured. A packing box 10 is formed in the upper part of the elbow and through this box the pump shaft 11 extends downward through the center of the pipe 5 and carries on its lower end the impeller 12. The lower end of the shaft is journaled in a bearing 13 set in a hub portion 14 and the pump casing 15. A tube 16 extends from the lower bearing to the packing box 10 above and surrounds the shaft as a shroud to protect the same from any fibrous or stringy material from being wound around it. The bed plate 6 has also cast integral with it vertical stanchions 17 and a top member 18, and in the center of this top plate is a boss 19 in which is screwed a thrust and guide bearing block 20. This guide block serves as a means of vertical adjustment for the pump shaft and to insure exact alignment it has in addition to the threaded portion a cylindrical portion 21 which is accurately fitted in a cylindrical counter bore in the boss, a lock nut 22, with a locking screw 23 holds the thrust block 25 fixedly in place when once adjusted. A ball bearing 23 is centrally located in the thrust block and two lock nuts 25 on the shaft support the shaft on the ball bearing and take the thrust due to the suction of the impeller. At 27 I show the usual form of flexible coupling between the motor shaft and the pump shaft to compensate for a slight misalignment of the motor and pump. It is to be noted that the guide and thrust bearing being supported in one integral piece with the packing box insures accurate alignment between these two bearings which would not be so easily attained if the packing box 40 was carried on a separate member like the top plate or the vertical pipe 5.

The pump casing which involves the principal feature of my invention has an impeller chamber 28 closed at the bottom by a bottom or suction plate 39 in which is the central suction orifice 40. A flange 41 on the upper side of the impeller runs in a pocket formed in the upper part of the impeller chamber and the impeller has holes 32 for admitting water into the pocket from the impeller chamber so as to maintain a balance of pressure on the two sides of the impeller. The periphery of the impeller chamber I form into two volutes 29 as shown in Fig. 6 instead of the single volute that has been customary in such centrifugal pumps. The chamber has, therefore, two cut-waters as shown at 30. When the water reaches the cut-water it passes into a volute pipe 31 which continues on circumferentially as shown in Fig. 4, turns inwardly up over the impeller chamber and into the central discharge opening 32 from which the water flows into the vertical discharge pipe 5. The object of this construction of discharge passages is to avoid abrupt

changes in the direction and velocity of the flow. It will be noticed that the water as it leaves the periphery of the impeller in a tangential direction continues to move in this tangential direction with constant velocity while gaining in volume during its passage through the volutes 29 in the periphery of the impeller chamber, and then entering the volute pipes 31 at this constant velocity and still moving in substantially the same direction it is gradually turned toward the center discharge, while at the same time gradually increasing in volume with a corresponding reduction in speed and increase in pressure. Upon reaching the center of discharge it is gradually given an upward turn by the upwardly curved swells shown at 32 with the result that it enters the discharge pipe 5 in a direction substantially parallel with the axis. There is, therefore, a minimum of differential velocity imparted to the water as it leaves the impeller and flows along in volute channels 29 and this minimum of differential impetus is maintained clear through the volute pipes 31 and into the central discharge pipe. From this it follows that there will be a minimum of eddies with a resultant increase of efficiency. The volute discharge passages being opposite and equal will bring only torsional stresses on the pump, thus avoiding any tendency to bend the shaft or to set up deleterious strains and vibrations.

I claim:—

1. A centrifugal pump having a pump casing characterized by an impeller chamber with one or more volutes formed in the periphery thereof and one or more volute passages leading from said impeller chamber to a central discharge. 100
2. A centrifugal pump the casing of which has an impeller chamber characterized by a volute periphery and a volute connecting passage leading circumferentially from said chamber and curving upward and inward to join a central discharge. 105
3. A centrifugal pump of the character described, comprising an impeller, and a pump casing having a central discharge opening and a multivolute impeller chamber and a plurality of volute passages leading from the volutes in the impeller chamber to the central discharge opening. 110
4. A centrifugal pump of the character described, comprising an impeller, and a pump casing having a central discharge opening and a multivolute impeller chamber with a plurality of volute passages leading circumferentially from the volutes in the impeller chamber and then turning inwardly to connect with the discharge opening. 115
5. A centrifugal pump of the character described, comprising an impeller, an impeller shaft and a pump casing, said pump casing having a central portion forming a 120

bearing for the shaft with a central discharge opening on one side of the said central portion and a multivolute impeller chamber on the other side and a plurality of volute passages leading circumferentially from the volutes of the impeller chamber in the direction of the line of flow and then curving inwardly to the discharge opening.

6. A centrifugal pump of the character described, comprising an impeller, an impeller shaft and a pump casing having a central discharge opening and a multivolute impeller chamber with a plurality of volute passages leading circumferentially from the volutes in the impeller chamber and then turning inwardly and upwardly into the central discharge.

HARRY A. PRINDLE.
